INVENTOR:

Carl Scheid

BY *Gartner & Co* ATTY'S.

UNITED STATES PATENT OFFICE.

CARL SCHEID, OF HARRISON, NEW JERSEY, ASSIGNOR TO THE DRAPER COMPANY, OF PORTLAND, MAINE.

SPINDLE.

SPECIFICATION forming part of Letters Patent No. 590,380, dated September 21, 1897.

Application filed April 19, 1897. Serial No. 632,744. (No model.)

To all whom it may concern:

Be it known that I, CARL SCHEID, a citizen of the United States, residing in Harrison, Hudson county, and State of New Jersey, have 5 invented certain new and useful Improvements in Spindles; and I do hereby declare the following to be a full, clear, and exact description of the invention, such as will enable others skilled in the art to which it appertains 10 to make and use the same, reference being had to the accompanying drawings, and to letters of reference marked thereon, which form a part of this specification.

The object of my present invention is to 15 provide a support for spinning-spindles by means of which said spindles are flexibly mounted on the spindle-rail and which support permits an oblique adjustment of the spindle.

20 The invention consists in the improved spinning-spindle-supporting means and in the combination and arrangement of the various parts thereof, substantially as will be hereinafter more fully described, and finally 25 embodied in the clauses of the claim.

Referring to the accompanying drawings, in which like letters of reference indicate corresponding parts in each of the several views, Figure 1 is a front elevation of a portion 30 of a spindle-rail, in which is mounted a spinning-spindle by means of my improved supporting means, certain parts being broken away and others shown in section to better illustrate the nature of my said invention; Fig. 2, a cross-sectional view through the lower portion of Fig. 1; Fig. 3, a view similar to Fig. 2, showing the spindle-supporting 35 tube obliquely adjusted; and Fig. 4, a top plan view of a certain adjusting-collar.

40 In said drawings, *a* represents the spindle-rail, provided with a vertical hole or opening *b*, and in its upper portion with an annular groove or recess *a'*, concentrically arranged with the hole or opening *b*. In the opening *b* is arranged a downwardly-extending bushing *c*, secured to the spindle-rail by means of the set-screw *c'* and provided at its upper portion with an annular flange *c''*, resting in the annular groove or recess *a'*. The lower 45 portion of said bushing is provided with an

eccentrically-arranged opening *c''*, adapted to be engaged by the annular flange *d'* of a collar *d*, which latter is adjustably secured to the tube *e* by means of the set-screw *d''*. Said tube *e* penetrates the central chamber *c''* of 55 the bushing *c* and rests with its annular flange *e'* on an intermediate elastic washer *f*, arranged on the flange *c''* of the bushing *c*. The tube *e*, containing step-and-bolster bearing for the whirl-driven spindle *g*, is of usual 60 and well-known construction.

The annular flange or shoulder *d'* of the collar *d* is eccentrically arranged to the said collar and to the hole or opening penetrating the same, as clearly shown in Fig. 4. When 65 the spindle *g* is in a perpendicular position, the opening in the collar *d* is parallel to and concentric with the chamber *c''* of the bushing *c*. Should it be desired to place the spindle at an angle to the spindle-rail, the collar 70 *d* is rotated or turned until the required position is obtained, in which position it is again secured to the tube *e* by means of the set-screw *d''*.

Having thus described my invention, what 75 I claim as new, and desire to secure by Letters Patent, is—

1. The combination with the spindle-rail of a bushing arranged in said rail and downwardly projecting therefrom and provided in 80 its lower portion with an eccentrically-arranged opening, a tube penetrating said bushing and provided with an annular flange, an elastic washer between said annular flange and the top of said bushing, a collar adjustably arranged on said tube and provided in 85 its upper portion with an annular eccentrically-arranged flange or shoulder, adapted to engage the eccentric hole in the bushing, and a whirl-driven spindle in said tube, all said 90 parts, substantially as and for the purposes described.

2. The combination with the spindle-rail provided with a vertical hole or opening and in its upper portion with an annular groove 95 or recess concentrically arranged with said opening, a bushing secured in said opening and provided with an annular flange resting in said annular groove or recess, and also provided in its lower portion with an eccen- 100

trically-arranged hole or opening, said tube penetrating said bushing and having its annular flange flexibly mounted on the annular flange of the bushing, a collar adjustably arranged on the tube and provided in its upper portion with an eccentrically-arranged flange or shoulder, adapted to engage the eccentrically-arranged hole or opening in said bushing, and a whirl-driven spindle in said tube,

all said parts, substantially as and for the purposes described.

In testimony that I claim the foregoing I have hereunto set my hand this 5th day of April, 1897.

CARL SCHEID.
